UNITED STATES PATENT OFFICE.

THEODORE M. PRUDDEN, OF GRAFTON, MASSACHUSETTS.

BELT SPlicer.

Application filed February 21, 1921. Serial No. 446,648.

To all whom it may concern:

Be it known that I, THEODORE M. PRUDDEN, a citizen of the United States, and resident of Grafton, county of Worcester, State 5 of Massachusetts, have invented an Improvement in Belt Splicers, of which the following description, in connection with the accompanying drawing, is a specification, like characters on the drawing representing like 10 parts.

This invention relates to improvements in belt splicers and the object thereof is to provide a novel and simplified one-piece metallic device for splicing belts, particularly such 15 belts as the tapes which are used for driving the spindles of spinning or twisting machines.

The usual method of splicing tapes for spinning machines and many other belts consists in lapping over the edges of the tape or belt to be spliced and sewing the overlapped portions of the belt together by a 20 portable sewing machine. The splice thus formed requires about 2 inches of tape to 25 form the joint and the sewing of the same is difficult after the tape has been lapped over the several pulleys which it drives as but little slack is available to allow manipulation of the tape in the sewing machines.

When the tape wears it usually breaks at the 30 sewed joint. The tape is then too short to be used unless a piece is spliced into it. The splicing of tapes in this manner, in any event, requires the use of a skilled sewing 35 machine operator and considerable time is consumed in transporting the sewing machine from place to place about the spinning or twisting room.

The present invention contemplates the 40 production of a metallic tape splicer which will fasten together the ends of the belt without the necessity of having extended overlapping ends.

In the splicing of such belts as tapes for 45 spinning and twisting machines and the like it is desirable that the strength of the splice or joint shall not exceed that of the tape itself so that if any breakage occurs it shall be in the splice. The present invention is 50 designed to produce a splice which will give way under less strain than that which would be required to break the tape and which can be readily replaced without the necessity of splicing on an additional piece of tape.

55 In am aware that heretofore metallic

splicers have been used, but such splicers have consisted of two or more parts which have to be assembled. Such devices require more or less skill in assembling and the parts thereof frequently become lost so that considerable difficulty is encountered in using them. 60

The object of the present invention is to provide a one-piece metallic belt splicer which can be readily applied by the usual 65 operator of the spinning machine.

A further object of the invention is to provide a metallic belt splicer which will grip the end portions of the belt with a toggle-like clamping action when the belt 70 splicer is applied thereto.

A further object of the invention is to provide a belt splicer of the character described which will lie upon the outer face of the belt and which will not contact with 75 either the face or the flanges of the driving pulleys when in use.

A further feature of the invention consists in providing a belt splicer of the character specified in which the body of the belt splicer 80 will cover and conceal the ends of the belt which are being secured together.

Other objects and features of the invention will more fully appear from the following description and the annexed drawings 85 and will be pointed out in the accompanying claims.

Preferred embodiments of my invention are illustrated in the annexed drawings, in 90 which,

Fig. 1 is a perspective view of one form of a one-piece metallic tape splicer in position to be applied to the ends of the tape;

Fig. 2 is a vertical longitudinal sectional view through the joint formed by the tape 95 splicer;

Fig. 3 is a perspective view of a different form of tape splicer embodying my invention;

Fig. 4 is a longitudinal sectional view 100 through the tape splicer and tape showing the joint made by the splicer illustrated in Fig. 3;

Fig. 5 is a detail view showing the tape ends to be spliced inserted in the tape splicer 105 in the position in which the splicer is adapted to be clamped upon the tape, the jaws of the clamping instrument being shown in cross section;

Fig. 6 is a similar view illustrating the 110

joint formed when the tape splicer has been clamped upon the tape by the jaws of the clamping tool; and,

Fig. 7 is a side elevation of a clamping tool showing the manner in which the splicer is applied to the tape.

The tape splicer which is illustrated in Fig. 1 comprises a body 1, preferably of sheet metal, which is desirably of slightly less width than the width of the tape to be spliced, and provided with a central rectangular opening 2 to receive the ends 3 and 4 of the tape or belt. The body portion 1 is provided with upturned ends 5 and 6 which desirably converge toward each other. One of the sides of the body portion desirably is provided with an integral extension 7 of a width slightly less than the distance between the bases of the upturned ends 5 and 6, the extension 7 being connected to said side by a relatively narrow strip 8 which is easily bent to enable the extension 7 to be folded down between the ends 5 and 6.

The extension 7 is bent into the form of an arch or an inverted V so that the sides 9 and 10 thereof form angularly disposed clamping elements, the edges of which are adapted to engage the end portions of the tape and when bent toward parallelism with the base, or toward the same plane, will produce a toggle-like action which will clamp the ends of the belt firmly against the upturned ends 5 and 6 of the body portion. The ends 5 and 6 may then be bent downwardly to cover the ends of the tape and to aid in retaining the clamping elements rigidly in clamping position.

By reason of this arched or V-shaped construction of the extension 7 the clamping elements 9 and 10 are in effect extensible, since as the extension 7 is bent toward parallelism with the base the edges of the clamping elements are forced outwardly away from each other into the clamping relation with the flanges of the body portion above described.

Another embodiment of the same inventive idea is illustrated in Figs. 3, 4, 5, 6 and 7 in which the tape splice is in the form of a sheet metal piece having a body 11 and upwardly turned flanges 12 and 13 which are the clamping elements and are disposed in angular relation to the base and to each other. When the clamping elements 12 and 13 are bent downwardly toward parallelism with the base, and consequently toward parallelism with each other, the adjacent edges 14 and 15 are forced toward each other and grip the ends of the belt, which are placed between them, with a toggle-like action.

The manner in which the splicer, illustrated in Fig. 3, is applied to the ends of the tape is illustrated in Figs. 5, 6 and 7 in which the clamping tool is illustrated as a pair of pliers having jaws 16 and 17, the

jaw 17 being provided with an open ended slot 18 of sufficient width to receive the two ends of the belt to be spliced.

In operation the ends of the belt are slipped edgewise into the slot 18, a sufficient amount of the tape protruding between the jaws to provide a suitable anchorage for the splicer. The splicer is then slipped endwise over the ends of the tape as illustrated in Fig. 5. The clamping jaws of the pliers are then squeezed together causing the clamping elements 12 and 13 to be bent toward the base 11. As the clamping elements 12 and 13 are thus bent toward the base 11 the adjacent edges are caused to approach each other and engage the outer faces of the ends of the tape with a toggle-like action increasing in pressure as said elements approach parallelism or alignment. When the tape splicer has been fully compressed upon the ends of the tape the ends are wholly enclosed within the splicer.

It will be noted that in splicing a tape by either of the constructions above described the splicer will lie wholly upon the outside of the tape and will, therefore, not come in contact with the face of the pulley. By forming the belt splicer of less length than the width of the tape the edges of the splicer will be prevented from engaging the flanges of the driving pulley.

When the splice formed by a splicer of the character above described becomes broken a new splicer may be readily applied since at most only a very short portion of one or both of the ends of the belt or tape will be broken off or will need to be removed and the stretching of the tape or belt when in use will readily supply the additional amount of stock required for the application of a new splicer.

Belt splicers of this character may also be employed for taking up the slack, in such belts as driving tape for spinning machine spindles, by merely forming a bight in the loose belt and forcing the same upwardly through the jaws of the splicing tool and applying the splicer to said bight in a manner above described.

It will be understood that the embodiments of the invention disclosed herein are illustrative and not restrictive and that various changes in form and construction may be made within the spirit and scope of the invention covered by the following claims which are intended to cover any form of one-piece belt splicers in which the clamping elements exert a toggle-like action upon the end portions of the belt or tape which are to be secured together.

Having thus described my invention, what I claim as new, and desire to secure by Letters Patent, is:

1. A belt splicer comprising a base adapted to cover the ends of the belt to be spliced,

pliable gripping elements disposed in angular relation to said base adapted, when said elements are bent toward parallelism, to exert a toggle-like clamping action upon the 5 ends of the belt and also to clamp the end portions of the belt against said base.

2. A one-piece belt splicer, adapted to cover the ends of the belt to be spliced together, comprising a member having extensible angularly disposed elements provided with belt-engaging edges adapted to engage the same face of the end portions of the belt and operating when bent toward the same plane to exert a toggle-like clamping action 10 upon the engaged ends of the belt which will clamp the end portions of the belt 15

against each other between said belt engaging edges and will also clamp the ends of the belt against said base.

3. A belt splicer comprising a metallic 20 plate bent transversely into substantially U-shape and presenting angularly converging elements having their edges spaced apart to receive the parts of the belt to be united therebetween and adapted, when bent toward the same plane, to clamp the parts of the belt therebetween and against each other with a toggle-like clamping action. 25

In testimony whereof, I have signed my name to this specification.

THEODORE M. PRUDDEN.
